DESIGN FOR A DEFLECTOR FOR INFANT'S TOILET SEAT

Walter S. Kraus, New York, N. Y.

Application November 15, 1937, Serial No. 72,897

Term of patent 7 years

To all whom it may concern:

Be it known that I, Walter S. Kraus, a citizen of the United States, residing at 43-10 Forty-Eighth Avenue, Woodside, city of New York, in the county of Queens and State of New York, have invented a new, original, and ornamental Design for a Deflector for Infant's Toilet Seat, of which the following is a specification, reference being had to the accompanying drawing, forming part thereof.

Fig. 1 is a front elevational view of a deflector for infant's toilet seat showing my new design; Fig. 2 is a rear elevation; and Fig. 3 is a side elevational view thereof.

I claim:

The ornamental design for a deflector for infant's toilet seat as shown.

WALTER S. KRAUS.
